UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

STOP MECHANISM FOR BUTTONHOLE-SEWING MACHINES.

1,115,936.

Specification of Letters Patent.

Patented Nov. 3, 1914.

Application filed March 15, 1913. Serial No. 754,487.

To all whom it may concern:

Be it known that I, GEORGE S. HILL, a citizen of the United States, residing at Strafford, in the county of Strafford and State of New Hampshire, have invented certain new and useful Improvements in Stop Mechanism for Buttonhole-Sewing Machines; and I do hereby declare the following to be a full, clear, and exact description of the invention, such as will enable others skilled in the art to which it appertains to make and use the same.

The invention relates to a safety device for buttonhole sewing or other machines in which mechanism is provided for stopping the machine or some mechanism of the machine in a predetermined position.

The object of the invention is to provide devices which will enable the operator to readily throw out the stopping devices when for any reason it is desired to turn the driving shaft by hand, and which will insure the return of the shaft and the parts driven thereby to the original stopping position before the machine is again operated by power, thus avoiding all danger of getting the parts of the machine out of time by the manual manipulation of the driving shaft.

To this end the invention consists in the features of construction and combinations of parts hereinafter described and referred to in the claims.

The invention will be readily understood from an inspection of the accompanying drawings and the following detailed description of the mechanism illustrated therein.

In the drawings, Figure 1 is a front elevation showing so much of a buttonhole sewing machine as is necessary to illustrate the application of the invention thereto; Fig. 2 is a detail sectional elevation showing the parts in stopping position; Fig. 3 is a detail plan view showing the means for rendering the stopping devices inactive in its normal position; Fig. 4 is a view similar to Fig. 2 showing the position of the parts when the driving shaft has been turned manually through a partial revolution; and Fig. 5 is a detail plan view of the parts in the position shown in Fig. 4.

In the drawings the invention is shown embodied in a buttonhole sewing machine having the construction and mode of operation of the machine fully shown and de-

scribed in applicant's prior application Serial No. 676,767, filed February 10, 1912. This machine in general comprises a cutter 1, a work clamp 2 which is moved to bring the work from cutting to sewing position, and is fed longitudinally and laterally during the sewing of a buttonhole, and stitch forming devices comprising an under needle and looper (not shown) mounted in a turret 3, and an upper needle 4 mounted to reciprocate in a rotary head, the turret and head being rotated in sewing about the end and about the eye of the buttonhole. The stitch forming mechanism and the mechanism for feeding the work clamp are driven during the sewing of the buttonhole from the sewing shaft 5 through a pulley 6 and clutch member 7 mounted on the shaft. The clutch member is secured to the shaft while the pulley is mounted to turn freely about the shaft and is moved to engage and disengage the clutch members through devices operated by a vertically movable rack bar 8 and oscillating sleeve 9. When the pulley is disengaged from the clutch member the shaft 5 and parts driven thereby are automatically stopped in a predetermined position by a stop arm 10 and a coöperating stop cam 11 formed on the hub of the clutch member. The stop arm 10 is secured to a vertical rock shaft 12 and is connected with a spring 13 which yieldingly supports the arm in position with the upper end of the shaft 12 against a stop screw 14, and also tends to swing the arm into the path of the cam 11. When the pulley is connected with the clutch member to drive the stitch forming and clamp feeding mechanism, the stop arm is held out of the path of the cam 11 against the tension of the spring 13 by a cam 15 which engages an arm 16 secured to the lower end of the shaft 12. When the pulley is disengaged from the clutch member the arm 16 is released by the cam, and the spring 13 tends to swing the stop arm 10 into active position, and to bring the upper end of a roll 17 carried by the arm into the path of the cam 11. At this time the roll 17 rides along the inclined side 18 of the cam 11, so that it moves gradually into the path of the cam. After the clutch pulley has been disengaged from the clutch member, the rotation of the shaft 5 continues under the inertia of the parts, and the end of the roll 17 on the stop arm rides

over a braking cam 19 which depresses the stop arm against the tension of the spring 13, thus gradually overcoming the momentum of the parts. As the end of the 5 roll 17 rides off of the cam 19 it is engaged by the abrupt rise on the stopping cam 11, so that the shaft 5 is brought to rest in predetermined position, as indicated in Fig. 2.

In the machine shown, the stopping devices are so arranged that the shaft 5 is brought to rest when the needles of the 10 stitch forming mechanism are retracted, the under needle being withdrawn below the work clamp where it is not conveniently accessible to the operator. In order that the 15 under needle may be rendered conveniently accessible, as for instance when it is to be threaded, it is desirable that provision be made for turning the shaft 5 through at 20 least a partial revolution by hand. Movement of the shaft 5, however, is prevented or resisted by the stop arm and cam, and means is therefore provided by which the operator may readily render the stopping 25 devices inactive, and the shaft 5 is provided with a knurled head 20 by which it may be manually manipulated. The turning of the shaft 5 through a partial or complete revolution after it has been stopped, 30 and before the machine is again started, may throw the mechanisms driven from the shaft 5 out of time with other mechanisms of the machine, and means is accordingly provided for insuring the return of the 35 shaft to its original position.

In the construction shown, the means for rendering the stopping devices inactive to enable the shaft to be turned by hand, and for insuring the return of the shaft to its 40 original position, comprise a bell crank lever the operating arm 21 of which extends into position where it may be conveniently reached by the operator, and the other arm 22 of which carries a cam 23 for engaging 45 the end of the stop arm 10 and swinging it into inactive position. The arm 22 of the lever is also provided with a projection 24 which is brought into the path of a stop shoulder 25 formed on a flange 26 of the 50 clutch member 7, when the lever is operated to move the stop arm 10 out of active position. The flange 26 is provided with a recess 27 which is in position to receive the projection 24 when the parts are in stopping 55 position, as indicated in Fig. 2. The flange is also provided with a locking surface 28 extending from the recess 27 to the stop shoulder 25 which engages the projection 24 when the shaft 5 is turned from normal 60 stopping position, and locks the projection 24 and bell crank lever in active position.

If the operator desires to manipulate the shaft 5 and stitch forming mechanism by hand when the machine is at rest, he swings

the bell crank lever from the position indicated in Fig. 2 to the position indicated in Fig. 4. During this movement of the lever the cam 23 swings the stop arm 10 out of active position, and the stop projection 24 enters the recess 27. The operator may now turn the shaft 5 forward until the stop shoulder 25 strikes the stop 24, as indicated in Fig. 4, when further forward movement of the shaft is prevented. The locking surface 28 acting against the end of the projection 24 prevents the return of the bell crank lever to the inactive position indicated in Fig. 2, so long as the shaft is out of normal stopping position. Before the bell crank lever can be returned to inactive position the cam shaft must be returned to the normal stopping position indicated in Fig. 2 when the recess 27 registers with the projection 24 and allows the bell crank lever to return to inactive position. The return of the cam shaft and parts driven thereby to the position in which they were stopped by the stopping devices is thus insured. The bell crank lever may be retained in either position 90 against accidental displacement by a spring pin 29, the conical end of which is adapted to engage one or the other of two notches formed in the lever.

While it is preferred to employ the specific construction and arrangement of parts shown and described, in applying the invention to the machine illustrated in the drawings, it will be understood that the invention is not confined in its application to this 100 machine, and that the construction and arrangement of the parts may be varied and modified as may be found desirable or best suited to the construction of the machine in which it is to be embodied.

Having explained the nature and object of the invention, and specifically described one form of machine in which it may be embodied, what I claim is:

1. A machine of the class described, having, in combination, a driving shaft, devices for arresting the shaft in a predetermined position, means whereby the operator may render the stopping devices inactive to enable the shaft to be turned by hand, and means for insuring the return of the shaft to its original position.

2. A machine of the class described, having, in combination, a driving shaft, stopping devices for arresting the shaft in a predetermined position, means under the control of the operator for rendering the stopping devices inactive and for limiting the movement which may be given to the shaft by hand.

3. A machine of the class described, having, in combination, a shaft, stopping devices for arresting the shaft in a predetermined position, means under the control of the operator for rendering the stopping de-

5 vices inactive and for limiting the movement which may be given to the shaft by hand, and devices for preventing the return of said means to inactive position while the shaft is out of its original stopped position.

4. A machine of the class described, having, in combination, a shaft, stopping devices for arresting the shaft in a predetermined position including a stop arm, a 10 manually operated cam for moving the stop arm out of active position, and supplemental stopping devices rendered active by the movement of the cam.

5. A machine of the class described, having, in combination, stopping devices comprising a stop arm 10, a manually operated lever provided with a cam 23 for rendering the stop arm inactive and with a stop projection 24, a stop disk provided with a recess 27, a locking surface 28, and a stop shoulder 25. 15
